UNITED STATES PATENT OFFICE.

PAUL H. GEIGER, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS AND ELECTRICAL APPARATUS SUITABLE FOR USE THEREIN.

Application filed October 29, 1923. Serial No. 671,368.

My invention relates to electrical apparatus, and particularly to railway traffic controlling apparatus suitable for use therein.

I will describe several forms of apparatus embodying my invention, and will then point out the novel features thereof in the claim.

In the accompanying drawings, Fig. 1 is a diagrammatic view showing one form of electrical apparatus embodying my invention. Figs. 2 and 3 are views showing modifications of the apparatus shown in Fig. 1 and also embodying my invention. Fig. 4 is a view showing one form of railway traffic controlling system based on the combination shown

in Fig. 1 and also embodying my invention. Figs. 5 and 6 are views showing railway traffic controlling systems based on the combination shown in Fig. 3 and also embodying my invention.

Similar reference characters refer to similar parts in each of the several views.

Referring first to Fig. 1, the apparatus in the form here shown comprises two windings 2 and 3 connected in multiple and reversibly supplied with current from a battery 9 through a pole-changer 8. Associated with winding 2 is a device A which constitutes means for permitting current flowing in one direction but not in the other to pass through the winding 2. This device A is a uni-directional current-carrying device or asymmetric unit, and it may, for example, be similar to the units shown in an application filed by L. O. Grondahl and F. H. Nicholson on the 7th day of March, 1922, Serial No. 541,733. This particular type of asymmetric unit is not essential to my invention, however, it being understood that any unit or device which will transmit more current flowing in one direction than in the other, will serve the purpose.

The direction of high conductivity in the device A is indicated by the arrow. A similar asymmetric unit A' is associated with the winding 3. As here shown, each of these units A and A' is connected in series with the associated winding, and these units are so arranged that current flowing in one direction is permitted to pass freely through winding 2, but not through winding 3, whereas current flowing in the other direction is permitted to pass through winding 3 but not winding 2.

Interposed between the windings 2 and 3 and controlled thereby, is an armature con-

tact 4 co-operating with three fixed contacts 5, 6 and 7. When both windings 2 and 3 are de-energized, or are both equally energized, armature contact 4 occupies its intermediate position wherein contact 4-5 is closed. When winding 3 is energized and winding 2 is de-energized or energized less strongly than winding 3, contact member 4 is swung to the right so that contact 4-6 is closed. When, however, winding 2 is energized and winding 3 is de-energized or energized less strongly than winding 2, the contact member 4 is swung to the left, so that contact 4-7 becomes closed.

It will be seen from the foregoing that when pole-changer 8 occupies one position so that current of one polarity is supplied to the windings 2 and 3, armature contact 4 is swung in one direction, whereas when pole-changer 8 occupies its other position so that current of the other polarity is supplied to the windings, armature contact 4 occupies its other extreme position. The apparatus constitutes, therefore, means responsive to reversals of current without the necessity for a permanent magnet or other polarizing medium.

Referring now to Fig. 2, the apparatus shown in this view is similar to that shown in Fig. 1, except that the two windings 2 and 3 with their mutually controlled contact member 4 are replaced by two relays 10 and 11 provided respectively with contacts 12 and 17. When pole-changer 8 is in one extreme position relay 10 is energized and relay 11 de-energized, whereas when pole-changer 8 is in the other extreme position relay 11 will be energized and relay 10 will be de-energized.

In Fig. 2 I have shown means for at times supplying alternating current instead of direct current to the relays 10 and 11, this alternating current being obtained from the secondary of a transformer 14, the primary of which is connected with a source of alternating current not shown in the drawing. The secondary of transformer 14 may be connected with the relays 10 and 11 by a switch 13, which, as illustrated, is open. Assuming this switch to be closed and pole-changer 8 placed in the intermediate position wherein battery 9 is disconnected from the rest of the apparatus, it will be seen that alternating current will be supplied to the relays 10 and 11. Dur-

ing one-half of each cycle the asymmetric unit A will permit current to flow freely through relay 10, and during the other half of each cycle the asymmetric unit A' will permit current to flow freely through relay 11, so that both relays will then be energized. It will be seen, therefore, that in the arrangement of apparatus shown in Fig. 2, one relay 10 or the other relay 11 or both relays will be energized according as direct current of one polarity or direct current of the other polarity or alternating current is supplied to these relays.

Referring now to Fig. 3, the two relays 10 and 11 are connected in series instead of multiple as in the preceding views. Relay 10 is provided with a shunt including an asymmetric unit A², whereas relay 11 is provided with a shunt including an asymmetric unit A³. These units are oppositely disposed, so that current of one polarity but not the other is forced to flow through relay 10, whereas current of the second polarity but not the first is forced to flow through relay 11. In the arrangement shown in the drawing, relay 10 is provided with an additional asymmetric unit A which freely passes the current which is forced by unit A² to flow through relay 10, but opposes the passage of the flow of current of the other polarity in relay 10. Relay 11 is similarly provided with an additional unit A' which freely passes a current that is forced by unit A³ to flow through the relay 11 but opposes the passage of current of the other polarity.

As shown in the drawing, the lower terminal of battery 9 is positive, so that with the pole-changer 8 in the position shown, current will flow through asymmetric unit A, relay 10, asymmetric unit A², and pole-changer 8 to battery 9, so that relay 10 is energized and relay 11 is de-energized. When pole-changer 8 is reversed, current will flow from battery 9, through the pole-changer, then through relay 11, unit A', unit A², and pole-changer 8 to battery 9, so that relay 11 will be energized and relay 10 will be de-energized. When pole-changer 8 is placed in an intermediate position and circuit controller 13 is closed, alternating current will be supplied to the relays, so that relay 10 will be energized during one-half of each cycle and relay 11 will be energized during the other half of each cycle, with the result that both relays will be closed.

In Fig. 3, it will be observed that relay 10 is provided with a shunt path including units A and A², which path offers a low resistance to current induced therein by the decay of flux in the relay core when the relay becomes de-energized. It follows that when the relay becomes de-energized this path retards the decay of flux in the relay core and so retards the opening of armature contact 12. In other words, this path gives the relay a slow-re-

leasing characteristic, and so has the same effect as a closed conductor around the core of the relay. The same thing is true of the path in shunt to relay 11 including units A' and A³. The same thing is also true of the relays 10 and 11 in Fig. 2 except that in this view the resistance of the shunt path for each relay is relatively high because the path includes the other relay, and so the period of retardation is reduced. In Fig. 1 each winding 2 and 3 is provided with a shunt path including the other winding and the units A and A¹, but the effect in this view is to quickly return armature 4 to its middle position when pole-changer 8 is moved to its middle position, because the current induced in the shunt path by the winding last energized serves to energize the other winding for a short interval of time.

Referring again to Fig. 2, and assuming that the pole changer 8 is open and switch 13 closed, when the upper horizontal wire is positive with respect to the lower, the current supplied to relay 11 through asymmetric unit A¹ causes a potential drop in the secondary of transformer 14. This potential drop reduces the electromotive force between the two horizontal wires and therefore reduces the potential drop across asymmetric unit A. As a result the current flowing through unit A in its high resistance direction and relay 10 is considerably reduced. Similarly, when the lower horizontal wire is positive with respect to the upper wire, the current supplied to relay 10 causes a potential drop in the secondary of transformer 14 which reduces the current then flowing through unit A¹ and relay 11. The result of this is that the current through either relay 10 or 11 in the undesired direction is held down to a relatively low value, and so a maximum of useful power is supplied to the load comprising these relays. In other words, the rectifier A¹ in series with relay 11 prevents the supply of an abnormal voltage to rectifier A, and vice versa. In Fig. 3, when the upper horizontal wire is positive with respect to the lower, current is supplied to relay 11 through units A¹ and A², and when the polarity of the electromotive force is reversed the potential across relay 11 and unit A¹ is shunted by unit A³, thereby preventing an abnormal current in the undesired direction through relay 11. In both Figs. 2 and 3, then, the current through an asymmetric unit in its high resistance direction is diminished by preventing an abnormal rise of voltage at the terminals of the unit, and this results in a net increase of useful uni-directional current for a given output circuit including a load and an asymmetric unit without increasing the voltage applied to the circuit.

Referring now to Fig. 4, the reference characters 15 and 15^a designate the track

- rails of a railway along which traffic normally moves in the direction indicated by the arrows, which rails are divided by insulated joints 16 into a plurality of successive sections D—E, E—F, etc. Located adjacent the entrance end of each section is a pair of windings 2 and 3 connected in multiple across the rails of the section, an asymmetric unit A being included in series with winding 2, and
- 10 an asymmetric unit A' in series with winding 3. These windings mutually control a contact member 4 as in Fig. 1. Current is reversibly supplied to the rails of each section adjacent the exit end of the section by means
- 15 of a battery designated 9 with a suitable exponent and a pole-changer designated 8 with a suitable exponent, which pole-changer may be operated by any suitable means not shown in the drawing. In order to simplify the de-
- 20 scription of the apparatus, I will term the windings 2 and 3, the associated asymmetric cells A and A', and the contact member 4, a relay device. Each relay device controls a signal designated by the reference character
- 25 S with an exponent corresponding to the location, each of which signals in the form here shown comprises three electric lamps G, Y and R. These lamps are arranged to project beams of green, yellow and red light, re-
- 30 spectively, and when lighted they indicate respectively, proceed, caution and stop. The proceed lamp G is provided with a circuit which passes from terminal B of a suitable source of current, through contact 4—7 of the
- 35 associated relay device to terminal C of the same source of current. Caution lamp Y is similarly controlled by contact 4—6, and the stop lamp R is similarly controlled by contact 4—5 of the associated relay device.
- 40 As shown in the drawing, the section immediately to the right of point F is occupied by a train W, so that both of the windings 2 and 3 of the relay device at point F are de-energized. Contact 4—5 being closed, signal
- 45 S^F indicates stop. Pole-changer 8^F is in such position that the upper rail in section E—F is positive, so that winding 3 of the relay device at point E is energized. Contact 4—6 of this device is accordingly closed, so that signal S^E indicates caution. Pole-changer 8^E is in such position that the lower rail 15^a of section D—E is positive, whereby winding 2 of the relay device at point D is energized and winding 3 of this device is de-energized.
- 50 Contact 4—7 of this relay device is accordingly closed, so that signal S^D indicates proceed. When the train W passes out of the section immediately to the right of point F, signal S^F will change to the caution indication
- 55 and pole-changer 8^F will then be reversed, so that signal S^E will change to the proceed indication.

Referring now to Fig. 5, I have here shown a four-indication signaling system using the arrangement of relays and asymmetric units

shown in Fig. 3. That is to say, two relays 10 and 11 are connected in series across the rails at the entrance end of each track section, and associated with these relays are four units A, A', A² and A³, so arranged that current flowing in one direction energizes one relay, whereas current flowing in the other direction energizes the other relay.

Each of the signals in the arrangement here shown is of the two-arm semaphore type, and each signal is controlled by the associated relays 10 and 11 in the following manner: When both relays are de-energized (see signal S^H) both semaphore arms 25 and 26 are in the horizontal position indicating 70 "stop." When relay 11 is energized and relay 10 is de-energized (see signal S^E) a caution indication circuit is closed for semaphore arm 25, which circuit passes from terminal B of a suitable source of current 80 through contact 21 of relay 11 and operating mechanism of semaphore 25 to terminal C of the same source of current. The signal then indicates "proceed prepared to stop at next signal". When relay 10 is energized and relay 11 de-energized (see signal S^E) the caution indication circuit for semaphore arm 25 passes from terminal B, through contact 18 of relay 10, and the semaphore arm operating mechanism to terminal C. A circuit for semaphore arm 26 is also closed, which circuit passes from terminal B, through back contact 17 of relay 11, contact 12 of relay 10 and the operating mechanism of arm 26 to terminal C. The signal then indicates "proceed 95 with caution". When both relays 10 and 11 are energized (see signal S^D) the circuit for semaphore arm 26 is open at back contact 17 of relay 11 but the caution circuit for semaphore arm 25 is still closed at contact 18 of relay 10. The proceed circuit for arm 25 is also closed, which circuit passes from terminal B through contact 19 of relay 10, contact 22 of relay 11, and the operating mechanism of arm 25 to terminal C. Semaphore arm 25 100 is then in vertical position so that the signal indicates "proceed".

As shown in the drawing, the section immediately to the right of point H is occupied by a train W, so that both relays 10 and 11 at point H are de-energized, with the result that signal S^H indicates stop. Current is now supplied to the rails of section F—H from the secondary of the transformer 29^H, the primary of which is constantly supplied with 115 alternating signaling current from a generator J through the medium of a transmission line 30. The circuit for section F—H is from the left-hand terminal of the secondary of transformer 29^H, through wire 31, the rail 15^a, and from rail 15, through reactance 24, wires 32 and 33, asymmetric unit A⁵, back point of contact 23 of relay 11 and back point of contact 20 of relay 10 to the right-hand terminal of the secondary of transformer 29^H. 120

Asymmetric unit A⁵ is so connected in this circuit that current can flow from the right-hand terminal of the transformer secondary to the left-hand terminal but not in the other direction, and, consequently, relay 11 at point F is energized and relay 10 at the same point is de-energized. The circuit for supplying current to the rails of section E—F is the same as the circuit for section F—H, except that the current for section E—F passes through asymmetric unit A⁴ and the front point of contact 23, instead of through unit A⁵ and the back point of contact 23. Consequently, at point F the current can flow from the left-hand terminal of the secondary of transformer 29^E to the right-hand terminal but not in the other direction. The result of this is that at point E relay 10 is energized and relay 11 is de-energized. The circuit for supplying current to the rails of section D—E passes from the secondary of transformer 29^E, through wire 31, the rail 15^a, and from rail 15 through reactance 24, wires 32 and 34, and the front point of contact 20 of relay 10 to the secondary of transformer 29^E. It follows that alternating current is supplied to the rails of section D—E so that both relays 10 and 11 are energized. Alternating current will accordingly be supplied to the section to the left of point D because relay 10 at point D is energized.

When the train W passes out of the section to the right of point H, relay 11 at point H will become energized, so that at point F relay 11 will become de-energized and relay 10 will become energized. Both relays 10 and 11 at point E will then become energized, so that signals S^E will then give a proceed indication.

Referring now to Fig. 6, the apparatus here shown is similar to that shown in Fig. 5, except that the signaling system is of the three-indication type. That is to say, each signal S is adapted to indicate "stop", "caution" and "proceed", and, as here shown, each of these signals is of the one-arm semaphore type. Each signal is provided with a caution indication circuit including contact 12 of the associated relay 10, and with a proceed indication circuit including contact 17 of the associated relay 11. It follows that each signal will indicate caution when relay 10 is energized, proceed when relay 11 is energized, and stop when both of these relays are de-energized.

As shown in the drawing, the section imme-

dately to the right of point F is occupied by a train W, so that both relays 10 and 11 at point F are de-energized, with the result that signal F^r indicates stop. The rails of section E—F are now supplied with current which passes from terminal B of a suitable source, through back contact 22 of relay 11, back contact 19 of relay 10 to lower rail 15^a, and from upper rail 15, through back contact 18 of relay 10, back contact 21 of relay 11 to terminal C of the same source. This current is in such direction as to energize relay 10 at point E but not relay 11 at the same point. Signal S^E accordingly indicates caution, and current is supplied to the rails of section D—E from terminal B, through front contact 20 of relay 10 to the upper rail 15, and from the lower rail 15^a through front contact 27 of relay 10 to terminal C of the same source. This current flows in such direction that at point D relay 11 is energized and relay 10 is de-energized. Signal S^D accordingly indicates proceed, and the supply of current to the rails of the section to the left of point D is as follows: from terminal B, through front contact 23 of relay 11 to rail 15, and from rail 15^a, through front contact 28 of relay 11 to terminal C. This current flows in the same directions as that supplied to section D—E, so that at the next point to the left of point D relay 11 will be energized and relay 10 de-energized.

Although I have herein shown and described only a few forms of apparatus embodying my invention, it is understood that various changes and modifications may be made therein within the scope of the appended claim without departing from the spirit and scope of my invention.

Having thus described my invention, what I claim is:

In combination, two windings, asymmetric units associated with said windings for permitting currents of one polarity but not of the other to flow through one winding and for permitting current of the second polarity but not of the first to flow through the second winding, means for supplying direct current of one polarity or the other to said windings to selectively energize one winding or the other, and means for supplying alternating current to said windings to energize both windings.

In testimony whereof I affix my signature.

PAUL H. GEIGER.
